UNITED STATES PATENT OFFICE.

WILLIAM THOMLINSON, OF SEATON CAREW, WEST HARTLEPOOL, ENGLAND.

METHOD OF CONSOLIDATING FLUE-DUST FOR USE IN THE MANUFACTURE OF STEEL.

No. 923,605.

Specification of Letters Patent. Patented June 1, 1908.

Application filed June 3, 1908. Serial No. 436,521.

To all whom it may concern:

Be it known that I, WILLIAM THOMLINSON, a subject of the King of Great Britain and Ireland, residing at Seaton Carew, 5 West Hartlepool, in the county of Durham, England, have invented certain new and useful Improvements in Methods of Consolidating Flue-Dust for Use in the Manufacture of Steel; and I do hereby declare 10 the following to be a full, clear, and exact description of the invention, such as will enable others skilled in the art to which it appertains to make and use the same.

This invention relates to a method for 15 the consolidation of flue dust, pulverized or finely divided iron ore, purple ore, pyrites residues or other materials containing iron, manganese, or other metals, into dried or calcined blocks, lumps or pieces, for use in 20 the purposes of manufacturing iron or steel. The usual method of treating these materials is by molding them into briquets either by manual labor, or by machinery and manual labor combined, to be afterward 25 dried, or dried and calcined or burned. This involves a good deal of manual labor, as such briquets have to be first molded, and when sufficiently set, to be conveyed from a molding shop to a drying kiln, and when 30 subsequently dried, piled or set up in stacks for burning in the kiln, each briquet being separately handled during the process.

The object of my invention is to avoid 35 these expensive manipulations and to render such materials easy to handle in large masses, and to widen in this way the employment of the materials, for by my process raw material with a comparatively small percentage of metal can be utilized, which 40 by the older and more costly methods its use is debarred by reason of the cost of the process of manufacture.

To carry out my invention, I put this 45 material through an ordinary pugging, mixing or grinding mill to obtain more homogeneity and to increase to some extent its binding properties. With all materials this may not be necessary, and in some cases certain materials, particularly 50 where they have a slight natural or artificial admixture of clay, or other cohesive substance, may be conveyed direct to the kilns for molding and burning. Generally speaking, previous milling is an advantage and 55 subsequent compression, either manual or

by machinery, to obtain additional solidification is an advantage, but this is not in all cases essential to my invention. It is merely an adjunct which from time to time may be of service.

In order that my invention may be clearly understood and readily carried into effect, I will proceed to describe the same, and for that purpose shall refer to the accompanying drawings, in which—

Figure 1 is a longitudinal sectional elevation of a subdivided mold and kiln for consolidating the material *in situ* according to my invention, corresponding to which Fig. 2 is a transverse sectional elevation. Figs. 70 3 and 4 are transverse sectional views similar to Fig. 2, but showing an alternate method of effecting the purpose of my invention.

In carrying out the invention, I convey 75 the material from the stock heap, mixer, grinder or pugging mill, direct to the kiln, either by manual labor or by bogies or wagons, or by a crane operated in any of the well-known ways. The kiln *a* may be 80 open topped, or may be attained in other ways and notably by long movable lateral partitions which may be either drawn out or lifted out by a crane or other appliance. Passages *d* and *e* below and at the sides can 85 also be provided by recesses in the brick-work of the kiln. The holes marked *c* may be in different places in the various lumps, if so desired, and the channel *d* may be of various widths. Channels of a similar kind 90 for the passage of the gas or heat may be also arranged in the side walls of the kiln. This not only insures hard burning but makes the subsequent handling and breaking up easy.

Where a crane is employed in the molding process, the resultant product may be removed by its aid when properly burned, and deposited in a place convenient for loading or for treatment in smelting.

Referring to Figs. 3 and 4, another method by which my process may be utilized in kilns with the usual closed tops is to mold directly into large masses at the point where the material to be treated can be most conveniently delivered, either from stock piles, or from the mills or mixers, into large molds, subdivided, perforated, or entire, which molds are when sufficiently solid, or immediately when artificially compressed,

stripped, and the mass conveyed to the kiln or burning flats on bogies or wagons suitably arranged. The floor of the kiln is hollowed at *d* and fitted with movable rails *f*.
5 By an ordinary lever arrangement the mass is lowered so that it is carried on the side projections of the floor and the bogie or wagon, and ultimately the rails are withdrawn, leaving the mass in position as
10 shown in Fig. 4.

The burned masses may be withdrawn by the reverse operation.

The simple method of treatment, the handling in large bulk and the excellence of the
15 material produced, when compared with the ordinary method of treatment, the handling in small pieces, the drying and subsequent piling and burning in kilns as briquets, and the heavy labor costs, show a large and material advantage, and a great saving in the
20 cost of manufacture; the novel methods of treating and handling enable an excellent product free from smalls to be obtained, which in the case of metallurgical operations is an important factor.

It will be observed that in handling the material in large masses, it can be molded in a rough and ready manner, by simply charging the same into a molding box suitably
30 subdivided, and around suitable cores to form the channels *c*. These channels are of great importance in carrying out the process, for they serve as passages for the hot gases, and thereby facilitate and promote the
35 consolidation or drying step of the process. In addition to this these passages *c* serve in the completed product to furnish lines of easy fracture, and thereby to aid in breaking up the large finished masses into suitable lumps for charging into a blast furnace.

I wish it to be understood that the invention is applicable to flue dust, pulverized or finely divided ore, purple ore, pyrites, resinous, or other material containing iron, manganese or other metals, or a mixture of some or all of these; and therefore the term flue

dust, as found in the claims, is to be understood as covering any or all of such materials.

Having thus described my invention, what
I desire to claim and secure by Letters Patent
of the United States, is—

1. The process of forming flue dust material into lumps suitable for charging into a blast furnace, which consists in suitably
55 molding said material into masses provided with channels, and then utilizing said channels to aid in breaking up said masses into lumps of a size suitable for charging into said furnace, substantially as described. 60

2. The process of forming flue dust material into lumps suitable for charging into a blast furnace which consists in suitably
65 molding said material into masses provided with channels; passing hot gases through said channels to solidify said material, and then utilizing said channels to break up said masses into lumps suitable for use in said furnace, substantially as described.

3. The process of forming flue dust material into lumps suitable for charging into a blast furnace which consists in suitably
70 grinding, mixing and molding said material into masses provided with channels; passing hot gases through said channels to solidify
75 said material, and then utilizing said channels to break up said masses into lumps suitable for use in said furnace, substantially as described.

4. The process of forming the materials
hereinbefore referred to into dried or calcined blocks for use in the manufacture of
iron or steel, which consists in consolidating
80 said material into masses having vertical
division spaces therein and longitudinal
85 channels therethrough, substantially as described.

In testimony whereof, I affix my signature, in presence of two witnesses.

WILLIAM THOMLINSON.
